UNITED STATES PATENT OFFICE.

WADE F. WEBB, OF KERNVILLE, CALIFORNIA.

UNLOADING-MACHINE FOR RAILROAD-CARS AND THE LIKE.

1,368,081.

Specification of Letters Patent.

Patented Feb. 8, 1921.

Application filed August 7, 1919. Serial No. 316,454.

To all whom it may concern:

Be it known that I, WADE F. WEBB, a citizen of the United States, residing at Kernville, in the county of Kern and State 5 of California, have invented new and useful Improvements in Unloading-Machines for Railroad-Cars and the like, of which the following is a specification.

My object is to make an unloading machine for railroad cars and the like, and my 10 invention consists of the novel features herein shown, described and claimed.

My present invention is an improvement upon my unloading machine for railroad 15 cars and the like, patented April 16, 1918, No. 1,263,170.

Figure 1 is a side elevation of an unloading machine for railroad cars and the like embodying the principles of my invention, 20 the view being taken looking in the direction indicated by the arrow 1 in Figs. 2 and 3.

Fig. 2 is a front elevation looking in the direction indicated by the arrows 2 in Figs. 25 1 and 3.

Fig. 3 is a top plan view looking in the direction indicated by the arrows 3 in Figs. 1 and 2.

Fig. 4 is an enlarged fragmentary vertical sectional detail as on the line 4-4 of 30 Fig. 1.

Fig. 5 is a view analogous to Fig. 1 and showing the elevator suspended and the other operating mechanism lowered so that 35 the unloading machine will not be top heavy in shifting into and out of position to work.

Fig. 6 is a fragmentary perspective showing the means for suspending the elevator as in Fig. 5.

40 Referring to the drawings in detail, the gondola cars 1 and 2 have straight upper edges 3 and 4, and the upper edges 3 and 4 of one car may be connected to the upper edges of an adjacent car by a bridge 5, so 45 that the upper edges of the cars form a continuous track upon which the unloading machine may run.

The truck frame 6 is mounted upon flanged wheels 7 and 8 and the wheels 7 and 50 8 run upon the upper edges 3 and 4 of the cars so as to support the frame 6. The end bars 6^a of the truck frame 6 are offset upwardly so as to pass over the brake wheels of the cars, and the wheels 7 and 8 have 55 wide treads so as to fit the cars of various widths. The screws 9, 10, 11 and 12 are

rigidly fixed to floor flanges 13 and the floor flanges are fixed to the frame 6 so as to mount the screws in vertical parallel positions and in the form of a rectangle. 60

Caps 14 are placed upon the upper ends of the screws, braces 15 connect the caps together and guy rods 16 connect the caps 14 to the corners of the frame 6 so as to hold the screws rigidly upright. 65

The platform 17 rests upon bearing plates 18 at its corners, said platform being within the rectangle formed by the screws 9, 10, 11 and 12. The second bearing members 19 are nuts screw seated upon the screws 9, 10, 70 11 and 12 and have ball races in their upper faces, and bearing balls 20 fit in these ball races, there being similar ball races in the lower faces of the bearings 18. Flanges 21 extend downwardly from the bearings 18 75 into annular grooves in the upper faces of the bearing members 19 to hold the bearing members 19 concentric to the loose holes 22 in the bearing members 18, so that the screws 9, 10, 11 and 12 will operate freely 80 and loosely through the holes 22.

Flanges 23 extend downwardly from the bearing members 18 around the bearing members 19, and pins 24 are screwed through the flanges 23 to engage the grooves 25 85 formed in the bearing members 19 to hold the bearing members 18 and 19 in operative relation to each other. Without the pins 24 the bearing members 18 may be raised or jarred sufficiently to displace the balls 20. 90

Bevel gears 26 are keyed to the hubs 27 extending downwardly from the bearing members 19. A shaft 28 is mounted in hangers 29 extending downwardly from the platform 17, and bevel gears 30 and 31 are fixed 95 upon the ends of the shaft 28 in mesh with the bevel gears 26 upon the screws 10 and 11. In a like manner a shaft 32 is mounted in hangers extending downwardly from the opposite side of the platform 17, and bevel 100 gears 33 and 34 are fixed upon the shaft 32 in mesh with the gears 26 upon the screws 9 and 12.

A shaft 35 is mounted in hangers extending downwardly from the platform 17, and 105 bevel gears 36 and 37 are fixed upon the ends of the shaft 35 and mesh with the bevel gears 38 and 39 fixed upon the shafts 28 and 32, so that by operating the shaft 35 the bearing members 19 upon the screws 9, 10, 110 11 and 12 are operated simultaneously to raise or lower the platform 17. Obviously

the screws 9, 10, 11 and 12 must have right and left threads, so that the bearing members 19 will go up or down simultaneously.

An engine 40 is mounted upon the platform 17, a reversible transmission gear 41 forms a part of the engine 40, and the driving shaft 42 forms an extension of the crank shaft of the engine. The shift lever 43 controls the reversible transmission gear 41, so that by operating the shift lever 43 the shaft 42 may be driven in either direction.

The winding drum 44 is loosely mounted upon the shaft 42. A rope 45 has one end connected to the drum 44 and the other end of the rope, not shown, may be connected to any suitable anchor. A clutch member 46 is slidingly splined upon the shaft 42 and operated by a clutch lever 47 to engage a clutch member 48 fixed to the winding drum 44, so that when the shaft 42 is operating the lever 47 may be manipulated to operate the drum 44 to wind the rope 45 to pull the unloading machine forwardly or backwardly upon the gondola car, or to wind the rope 45 from the drum.

A belt wheel 49 is loosely mounted upon the shaft 42, a clutch member 50 is slidingly splined upon the shaft 42 to move into and out of engagement with the clutch member 51 carried by the belt wheel 49, and a hand lever 52 operates the clutch member 50. A belt 53 is placed upon the belt wheel 49 and extends downwardly through the platform 17 around the belt wheel 54 fixed upon the shaft 35, so that by manipulating the hand lever 52 the platform may be raised or lowered as desired. Of course, the shift lever 43 must be manipulated to run the shaft 42 in the proper direction to raise or lower the platform.

Posts 55 extend upwardly from the platform 17 and a shaft 56 is mounted in bearings at the upper ends of the posts 55, and the bearings have removable caps 57. The shaft 56 extends through the upper ends of the swinging posts 58, and a shaft 59 is mounted in bearings in the lower ends of the swinging posts 58.

A chain 60 connects a sprocket upon the shaft 42 to a sprocket upon the shaft 56. Endless conveyer chains 61 run around sprockets upon the shaft 56 and upon the shaft 59 and carry buckets 62, said buckets extending substantially across the interior of the gondola car, and said buckets having teeth 62^a extending from their edges so as to dig up any material in the gondola car if the material is caked, as might be the case with sand, plaster and the like.

Guide rollers 63 and 64 are mounted upon brackets 65 and 66 and the brackets are secured to the side bars of the frame of the platform 17, so that the rollers will engage the chains 61 and press the chains inwardly after they pass over the upper sprockets as

required to dump the buckets, and so that when desired a bolt may be removed from each bracket 65 and 66 and the brackets swung out of the way when it is desired to suspend the elevator and lower the platform. The engine 40 drives the elevator by driving the chain 60 and the shaft 56. A shaft 67 is mounted upon the platform 17 at right angles to the shaft 42, and a bevel gear 68 upon the shaft 67 meshes with the bevel gear 69 upon the shaft 42.

A drum 70 is mounted at one side of the platform upon a shaft 71 and the shaft 67 is connected to the shaft 71 by bevel gears 72 and 73. An idler drum 74 is mounted at the other side of the platform from the drum 70, and a conveyer belt 75 runs around the drums 70 and 74, so that the material elevated by the buckets 62 is discharged upon the conveyer belt 75 and is discharged by the conveyer belt 75 outwardly at one side of the machine.

A spout may be provided to receive the material from the belt 72 and conduct the material into a wagon or other suitable receptacle. Side boards 76 and 77 serve to convey the material to the center of the conveyer belt 75.

As the unloading machine is moved longitudinally upon a gondola car with the wheels 7 and 8 running upon the upper edges of the car, and as the platform 17 is moved up and down and the unloading machine moved forwardly or backwardly practically the entire contents of the car may be elevated.

The entire machine is controlled by an operator standing upon the platform 17 and manipulating the shift lever 43, the clutch lever 47, and the clutch lever 52.

In order that the unloading machine may be handled for placing the machine in position for unloading the gondola cars and for removing the machine from the cars, it is necessary that the elevator be raised above the level of the wheels 7 and 8. It is desirable that the platform 17 and load upon the platform be lowered as far as possible, so that the machine will not be top heavy, and it is desirable that wheels be provided for moving the machine sidewise.

Wheels 78 and 79 are mounted in brackets 80 and 81 extending downwardly from the frame 6, said wheels 78 and 79 having axes crosswise of the axes of the wheels 7 and 8, and said wheels 78 and 79 being slightly raised so as to be out of the way when the machine is running upon the wheels 7 and 8. Any suitable bridge, such as the bridge 5 may be provided and placed under the wheels 78 and 79, or in position for the machine to be moved on to the bridge, so that the machine will run sidewise.

Arms 82 and 83 are rigidly fixed upon the brace 15 at one end of the elevator, and sim- 3

ilar arms 84 and 85 are rigidly fixed upon the opposite brace 15 at the other end of the elevator, so that when it is desired to suspend the elevator the platform 17 is raised 5 until the shaft 56 is above the arms 82, 83, 84 and 85. The caps 57 are removed from the bearings to free the shaft 56 and supporting bars 86 and 87 are placed under the ends of the shaft 56 and on top of the arms 10 82, 83, 84 and 85, and then the platform 17 is removed thus leaving the elevator suspended, as shown in Figs. 5 and 6. Then the platform 17 is lowered to its lowermost position and the principal part of the weight of 15 the machine, such as the engine platform, conveyer and so on is near the bottom of the machine.

Thus I have produced an unloading machine for railroad cars and the like comprising a carriage adapted to run upon the cars forwardly and backwardly, screws extending upwardly from the carriage, nuts upon the screws, bevel gears connected to the nuts, shafts and gears connecting the 20 bevel gears of the nuts to operate simultaneously, a platform supported upon the nuts, an engine upon the platform, a connection between the engine and the train of gearing operating the supporting nuts to 25 run the nuts up or down to raise or lower the platform, an elevator carried by the platform, a connection between the engine and the elevator for operating the elevator, and a connection leading from the engine, 30 and adapted to be connected to an anchor for moving the machine forwardly or backwardly upon the car; so that an operator may stand upon the platform and raise or lower the platform, move the machine forwardly or backwardly, 35 and supporting the machine to run sidewise.

Various changes may be made without departing from the spirit of my invention as claimed.

I claim:

50 1. An unloading machine for railroad cars comprising a carriage adapted to run upon a gondola car forwardly and backwardly, screws extending upwardly from the carriage and rigidly secured thereto, nuts upon the screws, bevel gears carried by the nuts, shafts and gears connecting the bevel gears of the nuts together to operate the nuts simultaneously, a platform supported by the nuts, an engine upon the platform, and a reversible connection between the engine and the train of gearing operating the nuts to raise or lower the platform.

60 2. An unloading machine for railroad cars comprising a carriage, screws extending upwardly from the carriage and rigidly

secured thereto, nuts upon the screws, a platform resting upon the nuts, means on the platform for simultaneously operating the nuts to raise or lower the platform, a supporting frame work projecting upwardly 70 from the platform, an elevator arranged for operation upon said frame work and means on the platform for operating said elevator and for driving said unloading machine.

3. An unloading machine for railroad cars comprising a carriage adapted to run upon the cars forwardly and backwardly, screws extending upwardly from the carriage and rigidly secured thereto, nuts upon the screws, bevel gears connected to the nuts, 75 shafts and gears connecting the bevel gears of the nuts to operate simultaneously, a platform supported upon the nuts, an engine upon the platform, a connection between the engine and the train of gearing operating the supporting nuts to run the nuts up or down to raise or lower the platform, an elevator carried by the platform, a connection between the engine and the elevator for operating the elevator, and a connection 80 leading from the engine and adapted to be connected to an anchor for moving the machine forwardly or backwardly upon the car; so that an operator may stand upon the platform and raise or lower the platform, move the machine forwardly or backwardly, 85 and operate the elevator.

4. An unloading machine for railroad cars and the like comprising a carriage, a platform mounted upon the carriage, means 100 for raising and lowering the platform, an elevator mounted upon the platform, means for operating the elevator, an upright frame work for supporting said elevator, a motor carried by the platform and driving 105 connections between said motor and the platform raising and lowering means, the elevator operating means and the carriage.

5. In an unloading machine, the combination of a carriage having rollers, screws rigidly mounted on the carriage and extending upwardly therefrom, a platform mounted on the screws and adapted to be raised and lowered thereby, an engine mounted on the platform having a drive shaft and a reversible gearing operatively connected with said drive shaft, an elevator mounted upon the platform and operatively connected to said drive shaft, a cable drum mounted on the platform for moving the carriage longitudinally and operatively connected with the drive shaft a clutch mechanism between said drive shaft and the drum actuating mechanism, actuating mechanism operatively connected with said drive shaft for 115 raising and lowering the platform on the said screws and a clutch mechanism between said actuating mechanism and said drive shaft.

6. In an unloading machine, the combina- 130

tion of a carriage having rollers, screws rigidly mounted on the carriage and extending upwardly therefrom, a platform mounted on the screws and adapted to be raised and lowered thereby, an engine having a drive shaft mounted on the platform and having a reversing mechanism connected with said drive shaft, an elevator mounted upon the platform and extending therebelow, an actuating mechanism for said elevator connected with said drive shaft, a conveyer belt mounted on said platform transversely thereof and adjacent the said elevator, and operatively connected with said drive shaft, a cable drum mounted on the platform for moving the carriage long-

itudinally, said drum being operatively connected with said drive shaft, and a clutch mechanism between said actuating mechanism and the drive shaft, an actuating mechanism mounted on the platform for raising and lowering said platform, said mechanism being operatively connected with said drive shaft and having a clutch mechanism therebetween, and means whereby the elevator may be suspended and the other mechanism lowered for moving the machine. 20 25

In testimony whereof I have signed my name to this specification.

WADE F. WEBB.
